UNITED STATES PATENT OFFICE

TRAYHARN DAVIS, OF LOMITA, CALIFORNIA, ASSIGNOR OF ONE-HALF TO JULIUS H. BECKER, OF SAN FRANCISCO, CALIFORNIA

LIQUID FUEL BURNER

Application filed May 24, 1927. Serial No. 193,763.

This invention has to do with a burner for handling liquid fuel, and it is a general object of the invention to provide an efficient, practical and economical burner for handling crude oil, and the like.

It is a general object of this invention to provide an effective and improved mounting and control for an oil burner, or the like.

Another object of this invention is to provide improved features of construction for oil burners whereby the oil is handled in an effective and practical manner.

Another object of this invention is to provide an oil burner including an improved mounting for the rotating element.

It is another object of this invention to provide a burner of the character mentioned in which the bearing for the rotating element is protected against dust or other foreign matter.

It is a further object of this invention to provide a burner of the character mentioned in which the bearing for the rotating element operates without being subjected to the pressure of the air used in operating the burner.

The various objects and features of the invention will be best and more fully understood from the following detailed description of a typical form and application of the invention, throughout which description reference is had to the accompanying drawings, in which:

Fig. 1 is a side elevation of the construction provided by this invention showing the burner in operating position;

Fig. 2 is a view similar to Fig. 1 showing the burner down or out of operating position;

Fig. 3 is a plan view of the parts shown in Figs. 1 and 2;

Fig. 4 is an enlarged, detailed, vertical, sectional view of the burner proper provided by this invention; and

Fig. 5 is a detailed, transverse, sectional view taken as indicated by line 5-5 on Fig. 4.

The construction provided by this invention includes, generally, a base 10, a vertically movable burner 11, a guide ring 12 to guide and stop the burner in operating or firing position, supports 13 whereby the guide ring

12 is supported from the base 10, and means 14 for operating or moving the burner.

In the particular construction illustrated in the drawings, the base 10 is adapted to be arranged on a horizontal support and is in the form of a casting designed to be secured to the horizontal support and provided with parts for suitably carrying the other elements of the construction. The supports 13 for the guide ring 12 extend vertically from the base 10 and support the guide ring 12 in a horizontal position above the base. The supports may vary in number and formation. For purpose of example, I have shown three supports 13 in the form of rods, having their lower ends carried by the base 10 and their upper ends finished to receive and hold the guide ring 12.

The guide ring 12 is made sufficiently large to pass the upper end portion of the burner 11 and is provided with an inwardly extending flange part 16 which co-operates with a radially extending flange 17 on the burner to limit the upward movement of the burner through the ring.

The burner proper 11 is mounted on guides 18 for vertical movement so that it can be moved to an operating position where its upper end portion projects through the guide ring 12, as shown in Fig. 1, and a withdrawn or retracted position where it is removed from or below the ring 12, as shown in Fig. 2.

The means 14 provided for operating or moving the burner includes a hand lever 25 pivotally mounted on the base 10 at a point removed from the supports 13 and guides 18, a bellcrank 26 having one arm connected with the burner and the other arm connected with the lever 25 through a link 27. Springs 28 are provided on the guides 18 between the burner and base to normally yieldingly hold the burner in the up or operating position. A latch 29 is provided in connection with the operating lever 25 for releasably setting the lever in position where the burner is down, as shown in Fig. 2.

The burner proper 11 includes, generally, a vertically disposed cylindrical body A, a head B at the upper end of the body, a head C closing the lower end of the body, a rotor D mounted in the head B, a spindle E carrying

the rotor, a mounting F for the spindle, and various other parts, the details and functions of which will be hereinafter described.

The cylindrical body A is comparatively large in diameter and is provided at one side 5 with an intake opening 30 through which air or steam is introduced into the burner. The head B is applied to the upper end of the body A and is formed with a central opening 10 which carries the rotor D. The lower portion 31 of the opening in the head B extends upwardly and inwardly from the upper end of the body A to a middle or neck part 32 of reduced diameter. The upper portion 33 of the opening extends or diverges upwardly and 15 outwardly from the neck 32 in the manner clearly shown in Fig. 4.

The head C at the lower end of the body A is in the form of a plate applied to the lower 20 end of the body A to close it. In the construction illustrated in the drawings, tie-bolts 34 extend between the heads B and C to clamp the heads tightly to the ends of the body. In the arrangement shown in the drawings, the tie-bolts 34 extend between the heads B and 25 C within the body A.

A central post 36 is carried by the head C to project upwardly into the body A to form 30 a carrier or support for suitable bearings 37. The bearings 37 rotatably support a sleeve 38 which extends over or surrounds the post 36. The spindle E, which carries the rotor D, is arranged above the post 36 and is provided at 35 its lower end with an enlargement 39 which is screwthreaded to the upper end of the sleeve 38. By this construction, the spindle E is rotatably supported concentric with the body A and head B. In accordance with this invention, a housing 40 extends upwardly from the head C around the sleeve 38 and over the enlargement 39 on the stem forming 40 a chamber 41 around the bearings to carry lubricating oil. The top 42 of the housing is provided with a central opening which freely 45 passes the spindle E. A suitable oil supply pipe 44 extends through one side of the body A and connects into the housing 40 to supply lubricating oil to the chamber 41. With this arrangement, the bearings 37, supporting the spindle, operate in a bath of oil held by the housing 40.

The rotor D includes, generally, an upwardly opening cup 45, a flange 46 projecting outwardly in a radial direction from the 55 mouth or rim of the cup, and a mounting whereby the cup is carried by the spindle E. The spindle E projects upwardly through the bottom of the cup to about the level of the flange 46 at the mouth of the cup. A disc 60 48 is fixed on the upper end of the spindle E and carries a ring 49 having a plurality of spaced arms 50 projecting downwardly from it. The arms 50 carry a second ring 51 spaced below the ring 49. An annular flange 65 52 projects upwardly from the bottom of the

cup and is secured to the ring 51 by a suitable coupling member 53. The side wall of the cup diverges upwardly so that the cup is considerably larger at the mouth than at the bottom, as clearly shown in Fig. 4 of the 70 drawings. The cup is proportioned and related with reference to the head B so that its side wall is spaced a substantial distance from the neck 32 of the opening in the head, while the flange 46 at the mouth of the cup 75 is spaced somewhat above the upper end of the head. A plurality of vanes or blades 60 are provided on the exterior of the cup between the flange 46 and the side wall to project outwardly from the cup to fit the neck 80 part 32 and outer part 33 of the opening in the head with working clearance. It is to be understood, of course, that the blades 60 may be pitched or shaped so that they cause rotation of the rotor D upon air being delivered to the body A so that it is forced upwardly in the body to discharge through the head B around the cup of the rotor and between the blades. 85

A fuel supply pipe 65 extends into one 90 side of the body A and is connected with a vertically disposed tube 66 which extends upwardly around the spindle E with substantial clearance to a point opposite the arms 50. In the form of construction illustrated 95 in the drawings, the tube 66 projects upwardly from the top 42 of the housing 40, in fact, is formed integral with the top 42 of the housing. An outwardly extending flange 70 is provided at the upper end of the tube 66 100 to direct fluid overflowing from the top of the tube outwardly to pass between the arms 50 into the cup 45. In the preferred arrangement, the fuel tube 66 extends freely through the bottom of the cup of the rotor in the manner shown in Fig. 4 of the drawings. For the purpose of catching any liquid that may find its way out of the bottom of the cup, a flange 71 extends upwardly from the top 42 105 of the housing 40 around the lower end portion of the cup forming a catch basin. A suitable drain pipe 72 connects into this catch basin in the manner clearly shown in Fig. 4 of the drawings. 110

In accordance with my invention, a shielding tube 80 extends upwardly from the top 115 42 of the housing 40 around the spindle E to a point above the top of the fuel tube 66. The shielding tube 80 fits around the spindle E with clearance and fits within the fuel tube 66 with clearance. The tube 80 shields the spindle so that the liquid fuel introduced through the pipe 65 does not find its way into the housing 40. Further, the tube 80, in opening within the cup, protects the bearing 120 against pressure from air currents formed by the burner when the device is in operation,—the reason being that the top of tube 80 is well above the top of fuel oil tube 66. In the preferred construction, an over-hanging or 125 130

downwardly extending lip 85 is provided on the under side of the disc 48 to extend downwardly around the upper end of the shielding tube 80, protecting the upper end of the tube.

From the foregoing description, it is believed that the operation of the burner will be fully understood. For instance, when the burner is in operating position, as shown in Fig. 1, air is introduced into the body A of the burner through the opening 30 while liquid fuel is introduced through the pipe 65. The air, in discharging through the head B, causes rotation of the rotor D so that the liquid fuel overflowing from the tube 66 is carried to the mouth of the cup to discharge over the flange 46 and mix with the air discharging from the under side of the flange 46, giving an effective mixture of fuel and air for combustion.

Having described only a typical preferred form of my invention, I do not wish to limit myself to the specific details set forth, but wish to reserve to myself any changes or variations that may appear to those skilled in the art or fall within the scope of the following claims:

Having described my invention, I claim:

1. A burner of the character described including a body having a head closing one end, a post projecting into the body from the head, a spindle, a bearing rotatably mounting the spindle on the post, a cup carried by the spindle, a housing projecting from the head around the bearing, and a fuel supply conduit carried by the housing to extend around the spindle and into the cup.

2. A burner of the character described including a body having a head closing one end, a post projecting into the body from the head, a spindle, a bearing rotatably mounting the spindle on the post, a cup having an opening in its bottom to pass the spindle, spaced arms supporting the cup from the spindle, and a fuel supply conduit extending around the spindle and into the cup.

In witness that I claim the foregoing I have hereunto subscribed my name this 19th day of May, 1927.

TRAYHARN DAVIS.
